UNITED STATES PATENT OFFICE

WILLIAM BODGE, OF NUTLEY, NEW JERSEY, ASSIGNOR TO LEO STONE, OF BROCKTON, MASSACHUSETTS

ENVELOPE MACHINE

Application filed May 8, 1931. Serial No. 535,919.

- The present invention relates to envelope machines in which webs are led from a pair of paper rolls disposed one above the other and transversely cut to form opposite pairs of blank sections adapted to be assembled and secured together to form two-part envelopes closed along their side and bottom edges and having open sealing flaps at their top or mouth.
- 10 The objects of the invention include an envelope construction in which little or no waste of paper-stock is formed, and by its two-part blank formation the production of the machine is substantially doubled as compared 15 with the common one-piece envelopes of the side seam type of similar sizes.
- For further comprehension of the invention, and of the objects and advantages thereof, reference is had to the following description and accompanying drawings, and to the appended claims in which the various features of the invention are more particularly set forth.
- Referring to the drawings in which similar characters of reference designate like parts throughout the several views:
- Figure 1 is a diagrammatic side elevational view of a machine embodying my invention.
- 20 Figure 2 is an end elevational view of the machine.
- Figure 3 is a face view of the upper web showing the general shape into which the front blanks of the envelopes are cut during transit, together with gum lines thereon.
- Figure 4 is a face view of the lower web showing the relative cutting shape of the back blank and dotted score lines indicating side seam folding lines.
- 40 Figure 5 is a plan view of a folded envelope as delivered from the machine, showing the back member partially broken away to expose a portion of the folded seam thereof and the relative position of the gum line on the inner face of the front member.
- In the drawings numerals 10a and 11a respectively indicate upper and lower paper rolls of different widths centrally disposed transversely in line with each other and arranged with conventional tension devices, not
- shown, the rolls being supported in the usual manner upon shafts 10b and 11b, mounted for rotation in bearings carried on the opposite side frames 12 of the machine.
- The upper web 10 leading from the paper roll 10a is of relatively narrow width and passes between a pair of feeding rollers 13 from which point it continues its travel at a uniform velocity between the pair of side-cutting rolls 14 and 15, respectively provided with detachable side-cutting discs 14a and 15a, the former arranged with knife members 14b and the latter with hardened surfaces that coact with the knives to trim the opposite side edges of the web and form beveled portions thereon as indicated at 14c, Figs. 3 and 5. The chips formed by the side-cutting rolls may be removed from the machine in well-known manner, as by an air-suction device.
- From the side-cutting rolls the web passes between a pair of cross-cutting rolls 16 and 17, the latter arranged with a pair of knives 18 extending lengthwise of the roll and adapted to coact with hardened surfaces on the opposite roll 16 and transversely sever the web along the line 18a, Fig. 3, and form front envelope blanks 19 having end extensions constituting top and bottom sealing flaps 19a and 19b respectively. In passing around the cutting roll 16, the partially severed blanks 19 are engaged by the gumming roll 20, having at opposite ends the discs 21 adapted to apply longitudinal gum lines 21a to the blanks, the gumming roll being also provided with die sections 22 for applying transverse gum lines 22a to the bottom flap 19b. Adjacent the gumming roll 20, a gum-supply box 23 is conveniently supported and provided with a rotary feed roller 24 that adjustably engages the gum supplying members of the gumming roll 20 and regulates the quantity of adhesive applied thereto, the several parts of the gumming device being arranged in well-known manner.
- The lower web 11 leading from the paper roll 11a is of relatively wider width than the upper web and passes between two pairs of feeding rollers 25 and 26, and intermediate of said pairs of rollers the opposite side edges

of the web are folded over upon the body portion thereof along the dotted lines 27, see Fig. 4, to form side connection seams 27a, the side folding device including a fixed transverse spacing bar 28 over which the seams are drawn and folded down by the longitudinally extending side folding blades 29 during the regular movement of the web, the said side seam folding device being of well-known construction. From the feeding rollers 26 the lower web passes between a pair of cross cutting rolls 30 and 31, the latter roll being arranged with a pair of knives 32 extending lengthwise thereof and adapted to coact with hardened surfaces on the opposite roll 30 and transversely sever the side folded web along the line 32a, Fig. 4, and form back envelope blanks 33 having a width over the folded side seams corresponding with the body width of the front blanks, and the length of the back blanks corresponding with the body length of the front blanks, as disposed between the end sealing flaps thereof.

In the formation of the different lengths of blanks herein shown, the separate pairs of transverse cutting rolls therefor are diametrically proportioned to respectively make two blanks at each revolution, and in their rotative movement the rolls are geared to make a common number of turns and successively present a front and back blank at regular intervals, thus necessitating a relatively slower speed for the lower web than for the upper one. From the pair of cutting rolls 30 and 31 the back blanks 33 are directed upwardly between the guide bars 34 for engagement by the pair of feed rollers 35, and from which the blanks are directed upwardly between the guide bars 36 and the pair of feed rollers 37 and 38, which rollers are rotated at a feeding speed common with that of the cutting roll 16, that also advances the front blanks of the upper web. As the back blanks are cut clear from the cutting rolls 30 and 31 the leading edges thereof enter between the pair of feed rollers 35, the feeding speed of which is accelerated to relatively advance the short blanks for registration with the body part of the front blanks, the acceleration being effected by suitably proportioned gears operated from the cutting roll 30 and driving the feed rollers 35, the said gears being indicated in dotted lines at 39 and 40. The cutting rolls 16 and 17 and the feeding rollers 37 and 38 are geared together by driving wheels on their respective shafts and afford a common feeding speed for the two-part blanks, the back blanks being suitably guided upwardly around the feeding roller 37 for collecting engagement with the cutting roll 16.

In collecting the back and front blanks together the latter are advanced with the top flaps 19a in the lead, on which no gum is applied, and in their advancement around

the cutting roll 16 the front blanks engage the gumming roll 20 and first receive the longitudinal gum lines 21a upon the body of the blanks, and then the transverse gum lines 22a upon the bottom flap 19b, the blanks 19 being then downwardly directed by guide bars 41 around said cutting roll and timed to effect registration with the upwardly moving opposite back blank 33 and the engagement between the side seams thereof and the gum lines of said front blanks, whereby the opposite blanks are caused to jointly pass between said cutting roll 16 and folding roller 37 and thus secured together. In the joint passage of the opposite blanks between the cutting roll 16 and feeding roller 37, the gummed bottom flap 19b of the front blank is folded over and secured to the outer surface of the back blank by a folding blade 42 slidably mounted in a guideway 43 and cam operated in the usual manner.

The two-part blanks as thus secured together with their top flaps 19a left open, are advanced between the two pairs of pressure rollers 44, from which they are fed in overlapping relation between a pair of endless pressure belts 45, carried upon slowly rotating rollers 46, and from which belts the work is delivered upon the table 47.

As herein shown the operating parts of the machine are driven from the motor 48 by a small pulley 49 fixed to the driving shaft thereof, and having a belt 50 leading to a relatively large pulley 51, fixed upon a stub-shaft 52 journaled in a bearing 53 mounted on a side frame of said machine, the stub-shaft being fixedly provided with a relatively small sprocket wheel 54 having a chain 55 leading to a relatively large sprocket wheel 56, fixed upon a shaft 57, on which is secured the cutting roll 16 and the gear wheel 58, the latter in turn driving the adjacent rolls and gum wheels in the directions shown by the arrows in Fig. 1, the remaining rotating parts being likewise driven indirectly from the same source of power.

I claim:

1. In an envelope machine, means for advancing a pair of webs, means for cutting said webs and respectively forming opposite front and back envelope blanks, the said front blanks having a body part and top and bottom sealing flaps projecting therefrom, and the back blank comprising a body part having side sealing flaps, means for applying gum lines to said front blanks, and means for collecting said opposite blanks to form envelopes having closed side and bottom portions.

2. In an envelope machine, means for advancing a pair of webs, means for cutting said webs and respectively forming opposite front and back envelope blanks, means for collecting said opposite blanks together, and means for sealing said collected blanks to

form envelopes having closed side and bottom portions.

3. In an envelope machine, means for forming a pair of opposite envelope members comprising front and back blanks, means for collecting said opposite blanks together, and means for sealing said collected blanks to form envelopes having closed side and bottom portions.
- 10 4. In an envelope machine, means for forming a pair of opposite envelope members comprising front and back blanks, said front blank having a body part and top and bottom sealing flaps projecting therefrom, and the back blank comprising a body part having side sealing flaps, means for applying gun lines to said front blank along the marginal side edges thereof and along said bottom flap, and means for collecting said opposite blanks together to form envelopes having closed side and bottom portions.
- 15 5. In an envelope machine, means for forming a pair of opposite envelope members comprising front and back blanks, said front blank having a body part and a bottom sealing flap projecting therefrom, and the back blank comprising a body part having side sealing flaps, means for applying gun lines to said front blank along the marginal side edges thereof and along said bottom flap, and means for collecting said opposite blanks together to form an envelope having closed side and bottom portions.
- 20 6. In an envelope machine, means for supporting a pair of paper rolls, means for advancing the separate webs therefrom, means for cutting said webs to respectively form opposite front and back envelope blanks, and means for jointly collecting and securing said opposite blanks together and form envelopes having closed side and bottom portions.
